DESIGN FOR A BUCKLE

William A. Nelson and Ralph L. Bringolf,
Houston, Tex.

Application June 16, 1942, Serial No. 107,214

Term of patent 7 years

To all whom it may concern:

Be it known that we, William A. Nelson and Ralph L. Bringolf, citizens of the United States, residing at Houston, in the county of Harris and State of Texas, have invented a new, original, and ornamental Design for a Buckle, of which the following is a specification, reference being had to the accompanying drawing, forming a part thereof.

Fig. 1 is a front elevational view of a buckle, showing our new design;

Fig. 2 is a side elevational view looking in the direction of the arrow "2"; and

Fig. 3 is an end elevational view, looking in the direction of the arrow "3".

We claim:

The ornamental design for a buckle, substantially as shown.

WILLIAM A. NELSON,
RALPH L. BRINGOLF.
